UNITED STATES PATENT OFFICE.

WILLIAM H. CRANE, OF WOODBURY, NEW JERSEY, ASSIGNOR OF THREE-FOURTHS TO HENRY M. LOVE, OF PHILADELPHIA, PENNSYLVANIA.

KEY-FASTENER.

SPECIFICATION forming part of Letters Patent No. 355,593, dated January 4, 1887.

Application filed July 29, 1886. Serial No. 209,402. (No model.)

To all whom it may concern:

Be it known that I, WILLIAM H. CRANE, a citizen of the United States, residing in Woodbury, county of Gloucester, State of New Jersey, have invented a new and useful Improvement 5 in Key-Fasteners, which improvement is fully set forth in the following specification and accompanying drawings, in which—

Figure 1 represents a front view of a key- 10 fastener for a rim-lock embodying my invention. Fig. 2 represents a vertical section of a portion thereof, the parts being in different positions. Fig. 3 represents a horizontal section in line $x\ x$, Fig. 1. Fig. 4 represents a 15 front view of a key-fastener employed for a mortise-lock.

Similar letters of reference indicate corresponding parts in the several figures.

My invention consists of a fastener for a 20 lock-key, whereby the latter is prevented from being turned from the outside of the door, the novel feature thereof being a securing device for a slide which engages with the key.

Referring to the drawings, A represents a 25 lock, which in Figs. 1, 2, and 3 is of the order of a rim-lock and in Fig. 4 of a mortise-lock.

On the face-plate B of the lock, surrounding the key-hole, are parallel bars C, which may be cast with or otherwise secured to said plate, 30 and form ways or guides for a slide or sliding plate, D, which is slotted, forming a bifurcation or fork, so as to embrace the shank of the key of the lock, it being noticed that said shank is flattened or angular, so that the walls of the 35 slot interlock therewith and prevent the rotation of the key, this feature, however, not being novel in itself.

In order to prevent movement of the slide D and consequent release of the key, I employ 40 a block, E, which is freely fitted in an opening, F, in the face-plate B, in a direction at a right angle to the slide D, so that when the latter is in closed or locked position it projects across and engages with the side of the 45 slide opposite to the slot or bifurcation of the same, and thereby prevents movement of the slide, especially from the outside. This block E has its inner end connected with a spring or spring-strip, G, which latter is secured to

the plate B and has attached to it a button, 50 H, which passes freely through said plate B, so that when the key is to be rotated for unlocking purposes the button H is depressed or forced in, whereby the block enters the lock and clears the slide, and thus the latter may be moved and the key accordingly released. 55 When the button is let go, the block E is held against the back of the slide, and when the key is locked the slide is moved into engagement therewith, the block then springing outward against the end or edge of the slide and securing the latter, the key being thereby fastened.

The lock-case is divided by a partition, J, which separates the works of the lock from 60 the spring G and inner end of the block E, so that should an implement be introduced into the lock through the key-hole from the outside it is prevented from reaching said spring and block, owing to said partition J, and thus 65 improper operation of the block is prevented.

For a mortise-lock a plate, B, is secured to the door, &c., at the place of occupation of the escutcheon, and provided with a slide and other features similar to the rim-lock, excepting the 70 partition J, which may be formed in the wood-work of the door, &c.

The slide D is, for convenience in operation, provided with a projecting portion or finger-piece, D', and secured to the plate B is a stop, 75 K, which serves to limit the movement of the slide when the same is disengaged from the key.

I am aware that it is not new to construct a lock having secured to the casing thereof a pivoted escutcheon adapted to be brought in 80 contact with the key and provided with fastening devices whereby the said key and escutcheon are securely held in place, and such I do not claim.

Having thus described my invention, what I 85 claim as new, and desire to secure by Letters Patent, is—

1. A key-fastener having a bifurcated slide, a lock-plate provided with guides for said slide, and an opening in the path of travel of said 90 slide, a movable block fitted in said opening, and a spring which has said block connected with it and is secured to the lock-plate, and 95

serves to hold the block engaged with the slide, said parts being combined and operating substantially as described.

2. A key-fastener formed of a bifurcated slide, guides for said slide, a block operated by a spring adapted to hold said slide in engagement with the key, and a stop secured to the

inside plate of the lock, adapted to limit the movement of the slide, the parts being combined and operating substantially as described. 10

W. H. CRANE.
